United States Patent Office

Des. 198,817
Patented Aug. 4, 1964

198,817

BOTTLE

George R. Stehl, Jackson Heights, N.Y., assignor to Bristol-Myers Company, New York, N.Y., a corporation of Delaware

Filed Oct. 21, 1963, Ser. No. 77,067

Term of patent 14 years

(Cl. D58—6)

Fig. 2.

Fig. 4.

Fig. 1.

Fig. 3.

Fig. 5.

The rear not shown is a mirror image of the front shown.

I claim:

The ornamental design for a bottle, as shown and described.
